J. J. L. Wright.

WITNESS:

UNITED STATES PATENT OFFICE.

WILLIAM C. BURNS, OF ALBANY, OREGON.

CUBOID-MUSCLE DEVELOPER.

Application filed July 26, 1922. Serial No. 577,660.

To all whom it may concern:

Be it known that I, WILLIAM C. BURNS, a citizen of the United States, residing at Albany, in the county of Linn and State of Oregon, have invented new and useful Improvements in Cuboid-Muscle Developers, of which the following is a specification.

My present invention has reference to an appliance for footwear and is in the nature of a support of such construction as to slightly elevate the outer side of the foot to effectively contact with the portion of the foot below the cuboid bone, and by virtue of the pressure thereagainst to increase circulation to effectively develop the cords and muscles that support the cuboid bone as well as the other bones of the foot.

A further object is to produce a combined cuboid bone support and muscle developer for footwear which may be readily arranged in any construction of shoes and which cannot slip when in position.

A still further object is to produce an article of this character which shall be of an extremely simple construction, cheap to manufacture and market, and which shall be thoroughly efficient for the purpose devised.

To the attainment of the foregoing, and other objects which will present themselves as the nature of the invention is better understood, reference is to be had to the drawing in which there is illustrated a satisfactory embodiment of the improvement reduced to practice.

In the drawing:—

Figure 1 is a side elevation of the improvement in applied position in a shoe, parts being broken away and parts being in section.

Figure 2 is a bottom plan view of the improvement.

Figure 3 is a fragmentary perspective view looking toward the inner face of the reinforcement.

Figure 4 is a bottom plan view showing the support provided with transverse elevating strips and with a leveler.

Figure 5 is a sectional view on the line 5—5 of Figure 4, the dotted lines illustrating the shoe in which the device is arranged.

Figure 6 is a sectional view on the line 6—6 of Figure 5.

In constructing shoes and foot appliances

for shoes, I have discovered that the use or walking on the muscles that hold the cuboid bone in place increases the circulation to an extent that the muscle tissues are built up to an extent that will strengthen the muscles 60 of the feet and ankles, and as these muscles return to normal position they hold the bones of the foot and ankle in normal position so that the cause of all foot troubles is thus removed. Therefore, I have termed 65 my improvement a cuboid muscle developer. The improvement is of a construction to relieve pressure of corns and callouses, and increases the wear of the shoe inasmuch as it carries most of the weight under the cuboid bone and muscles that hold the bone in place so that the foot is sustained straighter in the shoe, taking off the pressure on the toe and causing the shoe to wear more even on the sole and heel. 70

The support is made of two pieces of leather, one of which constituting a body 1 upon which the foot rests, and the other being in the nature of a reinforcing piece 2 which is adhesively secured to the under 80 face of the body 1 by a water-proof cement. Such construction, it will be noted, is extremely simple, and may be cheaply manufactured, there being no stitching between the parts, or analogous means for connecting 85 the same.

By reference to the drawing, it will be seen that the outer edge of the improvement is straight, and this edge is of course, disposed against the outer side of the shoe 3. 90 The outer straight edge overcomes the curved lines of the shoe and extends out under the muscles of the cuboid bone of the foot. Both the body 1 and the reinforcing strip 2 have their longitudinal edges beveled inwardly, the body member 1 having its heel and front portion likewise beveled, the last mentioned bevel being, for distinction, indicated by the numeral 4. The beveled edges permit of the device being snugly received 95 in the shoe, the beveled end 4 contacting with the insole of the shoe, as clearly disclosed in Figure 1 of the drawing. The reinforcing strip 2 is disposed a slight distance, say one-half an inch to the rear of the beveled end 4 of the body 1 and terminates a considerable distance from the outer edge of the heel portion of the said body 1. The outer end of the reinforcement 2 is 100 curved, as at 5, to correspond with the curv- 105

ature of the outer end of the body 1, while the inner end is straight, and the said straight end is provided with a transverse concavity 6 which starts a slight distance 5 from the straight edge of the said reinforcement, entering the opposite or curved edge thereof, the outer surface of the said depression being concaved, as clearly illustrated in Figure 3 of the drawing, and indicated by 10 the numeral 7. This depression takes the direct weight off of the cords of the foot that extends from the heel and serves to hold the bones of the foot properly positioned.

15 Under certain conditions I have found it desirable to build beneath the reinforcement 2, and as disclosed in Figures 4 and 5 and 6, I tack or otherwise secure transversely adjacent the ends of the reinforcing strip 2 building or elevating strips 8. These strips are comparatively thin and are constructed of leather. Any desired number of strips may be arranged one over the other in accordance with foot conditions 20 for the relief of foot troubles. In addition to this, I have found it necessary under other causes and conditions to arrange over the building strips 8 a longitudinally disposed leveler 9. This strip may be adjusted to either side of the device and is 25 designed to straighten the ankle. The depression 6 in the reinforcement 2 permits of the heel portion of the body being cupped by the pressure of the heel of the wearer thereagainst so that this construction also serves as a means for preventing the longitudinal displacement of the device 30 in the shoe. The support cannot move laterally because of its contacting engagement with the sides of a shoe. Movement of 35 the support longitudinally in the shoe is further prevented by the contacting engagement of the strips 8, the rounded end 5 of the reinforcement and the beveled end 4 of the body contacting with the insole of 40 the shoe.

The cause of so much foot trouble in the 45 human family is the neglect of the use of the muscles that hold the cuboid bone in place. These muscles become weakened like any other muscles that are not used, and as the weight of the body presses the bones of the foot down and out of their natural 50 position, the circulation is interfered with which causes the feet to tire quickly and become in a weakened condition. The weight is then forced against the cords of the feet, which causes cramps in the feet and the cords to ache in the legs. This condition 55 is frequently mistaken for rheumatism of the feet and legs and is effectively overcome by my improvement.

60 My improvement has the same effect upon a person's foot as were he walking barefooted on soft earth, it being well-known

that barefooted children develop the muscles of their feet to the highest extent and it is only when they are forced to wear shoes that the muscles begin to deteriorate and foot troubles commence, and it is thought 70 that the foregoing description, when taken in connection with the drawing will fully set forth the construction and advantages of the improvement to those skilled in the art to which such inventions relate.

75 Having described the invention, I claim:—

1. A cuboid support and muscle developer for shoes, comprising a flexible leather body whose heel end is round and whose opposite 80 end is struck at a curvature and beveled inwardly, said body having its outer edge straight and both edges of the body and the heel end thereof being beveled, a flexible reinforcing strip glued on the under face of the body at points adjacent to the rounded outer end thereof and inward of the heel portion of the body, and elevating strips secured transversely on the reinforcement, all as and for the purpose set 85 forth.

2. A cuboid support and muscle developer for shoes, comprising a flexible leather body whose heel end is round and whose opposite end is struck at a curvature and beveled 90 inwardly, said body having its outer edge straight and both edges of the body and the heel end thereof being beveled, a flexible reinforcing strip glued on the under face of the body at points adjacent to the rounded outer end thereof and inward of the heel portion of the body, elevating strips secured transversely on the reinforcement, and a leveler strip secured on the reinforcement strips opposite the straight edge 100 of the body, all as and for the purpose set forth.

3. A cuboid support and muscle developer for shoes, comprising a leather body whose outer edge is straight and whose edges and 110 ends are beveled whereby the said body will be snugly received in the shoe and the straight edge thereof positioned in the rounded outer side of the shoe, and a reinforcing strip secured on the under face of 115 the body adjacent to the outer end thereof for elevating the body at the portion thereof on which the cuboid bone rests, and transverse elevating strips on the reinforcing strip, and a leveler strip adjustably 120 secured on the reinforcing strips.

4. A cuboid bone support and muscle developer, comprising a leather body whose outer edge is straight and whose edges and 125 ends are beveled whereby the same are snugly received in the shoe to rest on the sole thereof and the straight edge to be received in the bulged portion on the outer side of the shoe, and also whereby the outer beveled end of the body will rest directly 130

on the insole, a reinforcing strip secured on the under face of the body adjacent to the outer end thereof for elevating the body at the portion thereof on which the cuboid 5 bone rests, said strip having its rear end provided with a transverse depression which terminates adjacent to the outer edge thereof, and the portions between the ends of

the reinforcing strip, the body and the insole of the shoe providing vacuum spaces 10 for preventing the slipping of the support in the shoe.

In testimony whereof I affix my signature.

WILLIAM C. BURNS.
